(57) **CLAIM**

The ornamental design for an upper ring of laparoscopic port system, as shown and described.

DESCRIPTION

FIG. 1 is a left side perspective view of the upper ring of laparoscopic port system of the present invention.

FIG. 2 is a right side perspective view of the upper ring of laparoscopic port system of FIG. 1.

FIG. 3 is a front perspective view of the upper ring of laparoscopic port system of FIG. 1.

FIG. 4 is a rear perspective view of the upper ring of laparoscopic port system of FIG. 1.

FIG. 5 is a top perspective view of the upper ring of laparoscopic port system of FIG. 1.

FIG. 6 is a bottom perspective view of the upper ring of laparoscopic port system of FIG. 1; and,

FIG. 7 is a three quarter perspective view of the upper ring of laparoscopic port system of FIG. 1.

It is certified that error appears in the above-identified patent and that said Letters Patent is hereby corrected as shown below:

On the title page, item (72) Inventors should read:

Joel Leroy, Bouvigny-Boyeffles (FR);
Michael Sauer, Tuttlingen (DE);
Sebastian Wagner, Bretten (DE);
Thomas Weishaupt, Sigmaringen (DE);
Daniela Wiest, Stockach (DE)

Signed and Sealed this
Twentieth Day of May, 2014

Michelle K. Lee
Deputy Director of the United States Patent and Trademark Office
